UNITED STATES PATENT OFFICE

ELMER V. LINDSTROM, OF JAMESTOWN, NEW YORK, ASSIGNOR TO DAHLSTROM METALLIC DOOR COMPANY, OF JAMESTOWN, NEW YORK, A CORPORATION OF NEW YORK

ENTRANCE INCLOSURE

Application filed February 19, 1932. Serial No. 594,023.

This invention relates to an improvement in entrance inclosures and particularly to those having door control or suspension mechanism which it is desired to conceal.

The preferred embodiment of the invention discloses an entrance inclosure preferably arranged for sliding doors having suspension means mounted in the head jamb and concealed from view by an adjustable cover plate.

The principal object of the invention lies in the provision of an entrance inclosure adaptable for sliding doors having a vertically adjustable cover plate by which access may be had to the door suspension mechanism.

Another object of the invention lies in the provision of a vertically adjustable inclosure cover plate which may be readily manipulated from the rear of the inclosure structure.

Other and further objects of the invention will be more clearly understood from a consideration of the following specification which is taken in conjunction with the accompanying drawing, and in which

Fig. 1 is a fragmentary rear elevation of one modification of this invention, showing the location of the cover plate with respect to the inclosure structure;

Fig. 2 is a vertical sectional view of the structure shown in Figure 1, being taken substantially on line 2—2 of that figure;

Fig. 3 is a fragmentary horizontal sectional view taken substantially on line 3—3 of Figure 1, and shows the engagement between the cover plate and the supporting structure of the head jamb;

Fig. 4 is a vertical sectional view similar to Figure 2, showing the forward projecting of the lower portion of the cover plate preparatory to lowering;

Fig. 5 is a further vertical sectional view, showing the cover plate lowered to expose a door suspension mechanism to view; and

Fig. 6 discloses the arrangement of brackets by which the cover plate is supported.

Reference is now had to the drawing in which is disclosed an entrance inclosure structure, generally indicated by the refer-

ence numeral 10. The inclosure shown is arranged to accommodate one or more sliding doors, indicated at 11. The head jamb 12 of the inclosure is formed with a flange 13 which, in conjunction with a plate 14, constitutes a lintel. The head jamb includes a horizontal flange 16, connected with the lintel flange 13 by a vertical portion 17. The flange 16 terminates in a vertical portion 18. Attached to the portion 18 is a face plate 20, the lower portion 21 of which projects below the horizontal flange 16 and together with flanges 16 and 17 provides a recess 23 in which a door suspension mechanism may be located.

Adjacent the ends of the head jamb and attached to the vertical flange 17, by bolts 24, are brackets 26. Each bracket is formed to provide a flange 27 substantially flush with the face plate 20 and the inner limit of the inclosure structure. An inwardly directed flange 28 terminates flange 27 and is in turn terminated by a rigidifying flange 29. The flange 28 is arranged with a guide-way or slot 31, which, in the present modification, takes the form of a longitudinally extending opening. The slot is arranged with a substantially central offset portion 32, the center of the offset being connected with a laterally directed slot 33. The slot 33 is formed with a pocket 34, the purpose of which will subsequently be brought out.

A cover plate 36, with which to inclose the head jamb recess 23, comprises a vertical portion 37 which is terminated along the lower edge by an inwardly directed flange 38. Joined to the inner face of the portion 37, adjacent the top of the plate, is a clip 40, the springlike portion 41 of which is engageable with the overhanging portion 21 of the face plate 20, when the cover plate 36 is in the position shown in Figure 2. The purpose of this clip is to prevent objectionable noises occurring through vibration of the cover plate at any time and particularly during operation of the door. Joined to the inner face of the portion 27, and adjacent the vertical edges of the cover plate, are blocks 43. Projecting outwardly from each of the blocks 43

is an arm 44. This arm is bent to parallel the cover plate, being of such length as to project beyond the end thereof in order that it may be received within the guideway 31.

5 It has been found preferable to provide two arms 44 at each vertical end of the cover plate. These arms are of such size as to freely move longitudinally of the guide-way.

It will be noted, (see Figure 2) that when 10 the cover plate is in position to inclose the recess 23, the upper arms 44 lie adjacent the upper end of the guide-ways 31 and the lower arms rest in the pockets 34 of slots 33. Engagement of the clip 40, with the overhanging portion 21, as well as the weight of the face plate precludes all possibility of objectionable vibration due to operation of the door.

When it is desired to gain access to the door 23 suspension mechanism or other control which may be located in the recess 23 above the door 11, the cover plate is raised slightly to disengage the lower arms 44 from the pocket 43. The lower arms on the cover plate may then 25 be withdrawn from slots 33 into the guide-way 31. The cover plate may now be dropped and both lower and upper arms 44 will travel downwardly through the guide-way to a position beneath the slot 33. The 30 cover plate, it will be noted, although moved to expose the recess 23 still lies in the same vertical plane that it occupied when in closed position. This arrangement is obviously advantageous when an inclosure structure of 35 this type is utilized on elevator shaft inclosures where it is essential that no part of the inclosure structure overhang or project into the hatchway. To return the cover plate to closed position, it need merely be raised to a 40 point where the top arms 44 reach the upper end of the guide-ways 31. The lower portion of the cover plate will then drop readily into the slot 33.

Although applicant has shown and described only one modification of his invention, and has shown the cover plate as moving downwardly to expose a door suspension mechanism, it is contemplated to reverse the open and closed positions through the provision of a somewhat higher head jamb. This 45 modification and any others which may be obvious to those skilled in the art are contemplated in so far as they are defined by the hereunto annexed claims.

50 Having thus set forth my invention what I claim as new and for which I desire protection by Letters Patent is:

1. In an entrance inclosure structure, a 55 head jamb having a recess for receiving a door suspension mechanism, a cover plate inclosing said jamb recess, a bracket joined to said jamb, said bracket being arranged with a generally vertical slot, a second slot opening into said vertical slot, guide arms joined to said cover plate and projecting into said

vertical slot, one of said arms being engageable with said second slot to retain said cover plate in one extreme position, said one arm being readily removable from said second slot to permit travel of said arms in said vertical slot whereby said cover plate may be moved to the other extreme position. 70

2. In an entrance inclosure structure, a head jamb having a door hanger recess therein, a bracket joined to said jamb adjacent one end of said recess, said bracket being arranged with two connecting slots, one perpendicular to the other, a plate inclosing said recess, arms on said plate projecting into one of said slots, one of said arms being engageable with the other of said slots whereby to support said plate in one extreme position. 75

3. In an entrance inclosure structure, a head jamb having a recess therein, a cover plate inclosing said jamb recess, a bracket joined to said jamb, a guide-way in said bracket, a pair of arms on said cover plate mounted in said guide-way and means forming part of said guide-way for engaging one of said arms whereby to support said plate in one extreme position. 80

4. In an entrance inclosure structure having a head jamb, walls defining a recess in said jamb, a face plate joined to said jamb and overhanging said recess, a cover plate for said recess, a clip joined to and forming with said cover plate a pocket for receiving said face plate, and cooperating means on said cover plate and said jamb for sustaining said cover plate in either open or closed position. 85

5. In an entrance inclosure structure, a head jamb having a recess therein, a slideable cover plate inclosing said jamb recess, a vertical guide element on said jamb, said element including a guideway having a laterally directed central portion, a slot opening into said lateral portion, arms on said plate projecting into said guideway, said slot serving to engage one of said arms whereby to support said plate when moved to one extreme position. 90

100 In testimony whereof I have affixed my signature.
